UNITED STATES PATENT OFFICE.

FRIEND A. RUSS, OF GREENWICH, CONNECTICUT, ASSIGNOR TO THE ROBERT N. BASSETT COMPANY, OF SHELTON, CONNECTICUT, A CORPORATION OF CONNECTICUT.

BUCKLE.

1,257,935.

Specification of Letters Patent. Patented Feb. 26, 1918.

Application filed June 11, 1912. Serial No. 702,982.

To all whom it may concern:

Be it known that I, FRIEND A. RUSS, a citizen of the United States, residing at Greenwich, in the county of Fairfield and 5 State of Connecticut, have invented a certain new and useful Improvement in Buckles, of which the following is a specification.

My invention relates to buckles for running webbing, and one of its objects is to provide a device of this character in which the same adjustment may be effected whether or not the buckle is strung so that its back face will be entirely covered with 15 webbing, or left naked or exposed. Another object is to provide a buckle which is capable of maximum adjustment on a minimum length of webbing, and a further object is to provide a buckle of minimum vertical dimension in which the extremity of 20 the webbing is secured thereto by swaging.

I attain these and other objects of my invention in the preferred embodiment thereof set forth in the following description and 25 accompanying drawing in which like reference characters refer to corresponding parts.

In the drawing:

Figure 1 is a front view of my buckle strung with webbing a portion of the latter 30 being broken away;

Fig. 2, a vertical section of the buckle shown in Fig. 1;

Fig. 3, a side view of the buckle before the webbing is attached thereto, and

Fig. 4, a vertical section of a modification.

My buckle consists of a back or frame A and a lever B. The back A is bent up out of a single piece of sheet metal to form lips 2 and 3 disposed at an angle to one another 40 as shown in Fig. 3. The front bar or lip 2 is provided with forwardly turned lugs or side ears 4, 4 which latter are pierced or perforated at 5, 5. The lever B may also be bent up out of sheet metal to form the front 45 or finger piece 6, the web engaging member 7 and the laterally projecting trunnions 8, 8, which latter are journaled in the perforations 5, 5. The strap or webbing C is fastened to the frame A by inserting its extremity k 50 between the open lips 2 and 3 which latter are then pressed or swaged together in a suitable machine to securely and permanently grip the webbing between them, as

shown in Figs. 1 and 2. In this manner the extremity of the webbing is not only gripped 55 between the face portions of the lips but also between their edges which latter extend transversely across the top of the back. After the webbing is secured to the buckle as above described the free or moving portion is passed rearwardly over the top edge 60 of the back lip 3 then downwardly below the back and then upwardly between the lever and the back into an upper reach. When the lever B is shut down it locks the 65 webbing in its adjusted position. The buckle thus strung forms an adjustable loop in the webbing which carries the cast off piece D or any other suitable member.

Although the stringing of the buckle, as 70 above described, covers up the back and produces the so called "rustless" effect yet it is obvious that the webbing may be carried forwardly over the edge of the front lip 2, instead of rearwardly over the edge 75 of the back lip 3, leaving the back lip 3 exposed or uncovered as shown in Fig. 4. It is to be noticed that either method of stringing requires the same length of webbing since the top edges of both lips are 80 equally distant from the bottom of the back A. It should be further noticed that the parts of the buckle embraced by the webbing are of the least vertical dimension required for fastening the end of the webbing 85 thereby leaving a maximum length of free webbing for adjustment purposes.

Since the broad feature of my invention resides in the construction of the back any suitable arrangement of the lever may be 90 employed provided it will clamp or hold the moving portion of the webbing. In Fig. 4 the lever trunnions are journaled lower down between the side ears than in the remaining figures so that the ears may be cut 95 down substantially even with the top of the back. This enables a metal blank of minimum vertical dimension to be utilized thereby saving scrap.

The particular meritorious feature of my 100 buckle, however, over those disclosed in the prior art resides in the fact that it can be made of a minimum amount of material and utilizes a minimum amount of webbing. This result is obtained by making the back 105 of the buckle, which is concealed when

strung with webbing and on display, since it is viewed from the front, of very light gage metal bent up to form a pair of the narrowest lips between the edges of which it is possible to fasten the webbing. Since the gripping action on the webbing is effected by the edges of the lips no increased vertical dimension need be given to their face portions since, as far as the gripping action is concerned, the gripping functions of the face portions could be entirely eliminated. For this reason the sheet metal blank from which the buckle is bent up need only be of sufficient vertical dimension to give body enough for a folding operation. In folding the metal to form the lips the back becomes reinforced so that the utilization of metal of lighter gage than that used in other buckles does not weaken the back.

20 Although the device above described embodies the preferred form of my invention yet the same is susceptible to such modifications as may fairly come within the scope of the appended claims.

Having now described my invention what 25 I claim and desire to protect by Letters Patent is:

1. A buckle comprising a sheet metal back provided with a pair of transversely disposed lips which are adapted to be swaged 30 on the end of a running webbing, and a web-holding lever hinged to said back, the said lips having their edges equally distant from the bottom of the back, whereby the same length of webbing may be used 35 in folding the latter either forwardly or rearwardly over the edge of one of said lips.

2. A buckle comprising a pivoted lever and a sheet metal back, the said back being formed of a blank folded midway of its 40 length to present a pair of transversely disposed edges along the top side of the back between which is gripped the extremity of a running webbing.

FRIEND A. RUSS.
